CLAIM

The ornamental design for a chair, as shown and described.

DESCRIPTION

FIG. 1 is a perspective view of the top, front and right side of a chair showing our new design;

FIG. 2 is a perspective view of the top, rear and left side thereof;

FIG. 3 is a front view thereof;

FIG. 4 is a rear view thereof;

FIG. 5 is a top plan view thereof;

FIG. 6 is a bottom plan view thereof; and,

FIG. 7 is a right side view thereof, a left side view being a mirror image thereof.

The dash-dash broken lines represent environment only and form no part of the claim.

1 Claim, 7 Drawing Sheets(56)
